The ornamental design for a hat, as shown and described.

DESCRIPTION

FIG. 1 is a front perspective view of a hat embodying my new design;

FIG. 2 is a left side view thereof;

FIG. 3 is a front view thereof;

FIG. 4 is a rear view thereof;

FIG. 5 is a right side view thereof;

FIG. 6 is a top view thereof; and,

FIG. 7 is a bottom view thereof.

The broken line showing of a pencil, a card, and lettering on the pockets illustrate environmental matter and form no part of the claimed design. The rows of broken lines on the edge of the visor and along each side of the gore seams, as well as the circular patch on the front of the crown, represent stitching, and form a part of the claimed design. The stippling represents texture.
